BILLFOLD

Charles D. Downes, Providence, R. I.

Application February 24, 1933, Serial No. 658,360

7 Claims. (Cl. 150—38)

This invention relates to a bill fold and has for one of its objects the provision of a bill fold which will be compact and yet one which will house a sufficiently large number of bills and fit within a small pocket or occupy a minimum amount of space within a lady's handbag.

Another object of the invention is the provision of a bill fold which may be of simple form and inexpensive to construct.

Another object of the invention is the provision of a bill fold formed from two parts secured together in an interlocking relation without the use of stitching, adhesive, or other binding means but which depend upon the slotting and shaping of the parts for retaining their desired relation.

Another object of the invention is the provision of parts which may be laid out upon a flat sheet of stock with the minimum amount of waste of the stock in the cutting and formation of the parts.

Another object of the invention is the provision of a construction which when in assembled relation affords a strap through which a belt or like part may be inserted to hold the bill fold in position and secure it against dislodgment.

Another object of the invention is the provision of a construction from which bills will not accidentally drop out, but which will require the bills to be withdrawn by pulling on the bill or bills with one hand while the other hand holds the bill fold and the remainder of the bills to be retained therein.

A further object of the invention is the provision of a bill holding device which will be slightly expandable in order that a varying number of bills may be included therein.

With these and other objects in view, the invention consists of certain novel features of construction, as will be more fully described, and particularly pointed out in the appended claims.

In the accompanying drawing:

Fig. 1 is a perspective view of the bill fold assembled with its parts in unfolded relation.

Fig. 2 is a perspective view of the body part of the bill fold.

Fig. 3 is a perspective view of the flap and strap portions of the bill fold.

Fig. 4 is a perspective view of the bill fold in folded position showing one side thereof.

Fig. 5 is a perspective view of the bill fold shown in Fig. 4 showing the opposite side thereof.

Fig. 6 is a section on line 6—6 of Fig. 5.

Fig. 7 is a section on line 7—7 of Fig. 5.

Both of these Figures 6 and 7 show the parts in greater expanded relation to better show their construction.

Fig. 8 is a perspective view illustrating the manner of inserting bills into the bill fold.

Fig. 9 is a perspective view illustrating the bill fold as mounted upon a woman's hose supporter.

Fig. 10 is an elevational view of the device mounted upon the belt of the wearer.

In the last two figures the foldable flaps are toward the body to prevent their being accidentally opened.

Frequently bill folds are made up from a plurality of pieces of material sewed together which construction is expensive, and which construction forms a rather bulky device to be carried about in the pocket, and in order to simplify the construction of a bill fold, and yet provide one which has all of the advantages of protecting and retaining the bills in position I have so shaped and cut two pieces of material that they may be interlocked one with the other and folded to provide the desired retaining and protecting means as well as provide a convenient mounting for the bill fold upon the person of the wearer, and the following is a detailed description of the present embodiment of this invention illustrating the preferred means by which these advantageous results may be accomplished.

A body portion designated 11 is cut out of some suitable sheet material such as leather or leathette in generally rectangular form. This body portion when finished will be folded along lines 27 and 28 to provide a middle or intermediate section and two end sections, and the middle section will be provided with slots 12 and 13 at substantially the center thereof and adjacent its opposite longitudinal edges. The slots 12 and 13 each have a tab 14 extending from the outer edge of the slot inwardly, which tab is formed by cutting out the stock in the shape shown in Fig. 2, this tab extending into the body portion along the edge 15 as there shown, which tab is for interlocking with another part to be presently described.

The strap and flap portions are formed in one piece as shown in Fig. 3 and also cut out from a single piece of sheet stock. This one piece formation includes a strap part 16 with flap portions 17 and 18 at either end thereof. The strap portion 16 is narrower than the flap portions whereby shoulders 19 and 20 are formed at the juncture of the strap 16 with the flaps 17 and 18. At the ends of the strap or at a point closely adjacent the shoulders 19 and 20

slits 21 and 22 are formed for the reception of the tabs 14, as will be presently described. The flap 17 is formed with a slot 23 while the flap 18 is provided with notches 24 providing head portion 25 and a neck portion 26 between the notches, which neck portion may lodge in the slot 23 in the interlocking of the flaps for retaining the bills in place.

To assemble the two parts illustrated in Figures 2 and 3 the portions of one of the flaps such as 18 which extend widthwise beyond the strap 16 will be folded inwardly upon itself and this folded end passed through the slot 13 thence carried along the outside of the middle section 15 of the body portion 11 and through the slot 12 whereby the flaps may be folded inwardly toward each other as shown in Figure 1, the members and the folds of the members being disposed at right angles to each other. The slits 21 and 22 are so located that they will be disposed substantially at the slots 12 and 13, and the tabs 14 will extend through the slits 21 and 22 as illustrated in Figure 6 to lock the member in position and the strap against movement along 25 the back of the body.

The flaps 17 and 18 are interlocked by the edges of the head 25 being folded inwardly and this head passed through the opening 23 in the flap 17 after which these folded edges may expand and the neck portion 26 be lodged in the slot 23 with the wider head portion 25 extending at either side thereof and preventing withdrawal of the head through the slot as illustrated in Figures 1 and 8. The two parts of the bill fold 35 are thus in assembled position and the body portion will be folded along lines 27 and 28 to cause the sections or cover portions 29 and 30 to overlie each other and also overlie the flaps and middle section and completely house any 40 bills inserted therein.

For the insertion of bills it is found that it is unnecessary to unlock the flaps 17 and 18, it being merely necessary to slightly arc the bill fold laterally as shown in Figure 8 and pass the bills 45 inwardly endwise beneath the flaps 17 and 18. It is also pointed out that the arcing of the bill fold in this manner serves to throw open the cover sections 29 and 30 which overlie the flaps when the device is in folded position.

50 The cover portions 29 and 30 also tend to have somewhat of an opening effect due to the inherent resiliency of this stock being folded along the lines 27 and 28 and as these cover portions tend to open they will exert a slight amount of pressure upon any pocket or the like in which the device is inserted tending to friction thereagainst and prevent movement of the bill fold from the pocket, this pressure being obtained by reason of the absence of any fastening device which also provides a more readily expandable unit to accommodate varying amounts of bills.

60 The strap portion 16 which extends along the back of the body member may be utilized to advantage for positioning a belt 31 through the strap 16 with the cover sections 29 and 30 positioned inwardly toward the body to prevent opening of the same, it being experienced by golf players many times that this is an advantageous way 65 of carrying money as it is not desired to carry the same in the pocket which may interfere with the play of the game.

70 This strap may also be utilized by women for mounting the bill fold upon a hose supporter 32 by passing the same through the strap portion

16 with the folds 29 and 30 inwardly toward the leg to prevent the same from opening and to thus secure the device in position. If additional security against opening is desired a rubber band 33 may be positioned about the device which band also assists in mounting of the device in position as illustrated in Figure 9 as it holds the same diagonally and prevents swinging about the hose supporter making an exact fit of the strap 16 and hose supporter unnecessary.

10 The slots 24 and the slot 23 are of such dimension that a sufficient amount of play is afforded thus giving expansion to the flaps and allowing various numbers of bills to be inserted in the bill fold without binding. There is, however, sufficient friction between the bills and the interlocked flaps 17 and 18 so that the bill fold may be grasped in one hand and shaken vigorously without dislodging the bills from position although this action is not ordinarily experienced in use.

15 The flaps 17 and 18 are of a width to cover substantially one third of the bill making a sufficient amount of covering to securely maintain the bill or bills therein. These flaps also stiffen the middle section of the body and act as a form for the bill fold defining a line of fold for the cover sections 29 and 30.

20 The foregoing description is directed solely towards the construction illustrated, but I desire it to be understood that I reserve the privilege of resorting to all the mechanical changes to which the device is susceptible, the invention being defined and limited only by the terms of the appended claims.

25 I claim:

30 1. An article of the general character described comprising two sheet stock members each having one dimension longer than the other, said members being generally right angularly disposed, one of said members being provided with slots and the other member having a portion of a width substantially the length of said slots and extending through the slots and having enlargements at points beyond said slots to hold the members in assembled relation, each of said members being folded upon itself at two spaced points providing an intermediate section and two end sections, the intermediate sections of said members overlying and said end sections overlying the intermediate sections when in folded position.

35 2. An article of the general character described comprising two sheet stock members each having one dimension longer than the other, said members being generally right angularly disposed, one of said members being provided with slots adjacent its opposite edges and the other member having a portion of a width substantially the length of said slots and extending through the slots and having enlargements at points beyond said slots to hold the members in assembled relation, the portion extending between said slots providing a strap by which the device may be secured in place.

40 3. An article of the general character described comprising a body folded to provide a middle section and two end sections, said end sections being foldable one over the other and both over said middle section, flap portions extending laterally of the body at generally right angles thereto, a strap for securing said flap portions together, and means for securing said flap portions and middle section together comprising slits in the middle section with the strap extending therethrough, said flat portions providing enlarge- 45

ments at points beyond said slits to prevent longitudinal sliding of the strap.

4. In an article of the general character described comprising a body folded to provide a plurality of sections, one of said sections having slots adjacent its edges, a strap extending over the outer surface of said slotted section with its ends extending through said slots and shoulders provided at the end of said strap to engage the material about the slot to lock the same in position.

5. In an article of the general character described comprising a body folded to provide a plurality of sections, one of said sections having slots adjacent its edges, a strap extending over the outer surface of said slotted section with its ends extending through said slots, and flaps integral with the ends of said strap of a width wider than said slot forming shoulders to engage the stock about said slot, said flaps being foldable inwardly over the inner surface of said section.

6. In an article of the general character described comprising a body folded to provide a plurality of sections, one of said sections having slots adjacent its edges, a strap extending over the outer surface of said slotted section with its

ends extending through said slots, said strap being provided with slits adjacent said slot and tabs on said section extending through said slits to secure said strap in position.

7. An article of the general character described comprising two separate right angularly arranged elongated sheet stock members with portions of one overlying portions of the other, means for assembling said members together comprising slots in one member through which the other member passes to provide interlocking engagement between them, said slots and member passing through them being of such relative size as to prevent lateral movement of the member in said slot, means forming an integral part of one of said members engaging and cooperating with a means forming a part of the other member to prevent the longitudinal sliding of one member through the slots in the other member, each of said members being folded upon itself to provide a plurality of overlying sections with the sections of one member overlying the sections of the other member and with the line of fold of one member being at right angles to the line of fold of the other member.
